UNITED STATES PATENT OFFICE

PAUL HOBRECHT, OF DUSSELDORF, GERMANY

MACHINE FOR BENDING AND TEMPERING LEAF-SPRINGS

Application filed December 12, 1928. Serial No. 325,452, and in Germany December 14, 1927.

Object of the invention is a machine for bending and tempering leaf-springs and such like, which renders possible an automatic and continuous working. In accordance with the invention any desired number of separate treatment devices may be disposed along the periphery of a drum. The pre-heated workpieces are placed into the separate treatment devices where they are bent and consecutively passed through a plunger-bath, being thereby simultaneously tempered and subsequently automatically ejected and conveyed.

The accompanying drawings illustrate the new device, in which

Fig. 1 represents a front-view, partly in section, of the apparatus.

Fig. 2 is a side-view of the same with the bending-device in section.

Fig. 3 is a sectional end elevation of a pair of adjustable jaws and a support for the saw blade.

Fig. 4 is a sectional side elevation of the parts shown in Fig. 3.

Fig. 5 is a top plan view of the same.

Fig. 6 is a view of the hydraulic actuating mechanism.

Upon a drum 1 and rotatably supported by standards 10 a plurality of bending-devices for leaf-springs, eight for instance, are equally distributed about the periphery of the drum. The bending-device consists of two pressure-jaws, a fixed one 3 and a movable one 4. The pressure-jaws support pressure-bars 5, 6, between which the leaf-springs are bent. The pressure-bars 5, 6 (see Figs. 3-5) are interchangeable and separately adjustable with the aid of a screw 7 and a wedge 8 which can be displaced along a groove 9 on the wedge-shaped rear of each pressure-bar 5, for the purpose of being able to adjust them in accordance with the desired degree of flexure. In order to support each leaf-spring 2 in its middle-position upon the pressure-bars, a special supporting device has been provided. This consists of plates 15 fitted with arms 11 on either side which are guided along eccentric grooves 12 in two rings 14 adjustable by means of a lever 13. The plates 15 are

equipped with cams 16 into which narrow supporting rails 17 (Figs. 3 and 4) are sunk and secured by screws. The rails are made to establish contact with an edge of the leaf-spring 2 and hold it fast in its middle-position upon the pressure-bars 5, 6. According to the width of the leaf-spring 2 all supporting rails 17 are moved jointly outwardly or inwardly by turning the rings 14, in such a manner, that the leaf-springs always occupy the middle-position opposite the pressure-bars 5. The supporting-rails 17 are made narrow, in order to permit the tempering medium, such as oil etc. to reach all points of the leaf-spring. For the purpose of enabling the spring-leaves to describe small longitudinal movements in conjunction with differences in tension, the ends of the pressure-bars are provided with rollers which are supported by ball-bearings 37.

The actuation of the moveable pressure-jaw 4 with the pressure-bars 6 for the purpose of bending the spring-leaf 2 placed in position is effected hydraulically by means of pairs of pressure-pistons 18, placed within cylinders 19 on the pressure-jaw 4, connected with the frame or with the pressure-jaw 3. The pressure-cylinders 19 belonging together are each connected with a valve device by means of feeding-pipes or rubber-tubing 20 and outlet-pipes 21. The valve device for instance, consists of a casting 22 carrying the piping establishing connection with the hollow shaft 24, and containing within an axially adjustable piston valve connected with bars 25, 26 projecting from the drum on either side. The latter act conjointly with cam members 27, 28, causing the guide-pistons to be displaced to the left or to the right, whereby the pressure-cylinders 19 are either placed under pressure or relieved of pressure.

Every bending device has, moreover, been provided with an ejecting-device for the completed work-pieces, which is made to consist of adjustable hook-arms 30 carried by a rock shaft 29 and which catch rake-like in between the pressure-bars 5, 6. The hook-arms are retained in their position by means of springs 31 and, on turning the

drum 1, contact rollers 32 carried by crank arms on shaft 29 engage a stationary frame contact 33, whereby the hook arms are swung outward, thereby ejecting the complete leaf-spring, which glide down guide surface 34 to a conveyor 35 removing it from the machine.

The preliminarily heated spring-leaves 2 are placed at point A (Fig. 2) between the opened pressure-jaws 3, 4. By turning the drum 1 the bar 25 is made to pass along the cam surface 27, thus causing the valve 22 adjusted to supply fluid pressure to actuate jaw 4 and the spring-leaf 2 is bent. The latter is then by rotation of the apparatus plunged into the oil-bath in the tempering tank in which the apparatus is arranged and tempered as the operation is continued. As soon as each bending-device has reached the point B after the drum has described a $\frac{3}{4}$ turn, the jaw 4 will be opened again in consequence of the bar 26 being moved by cam surface 28 and the completed spring will be released and ejected by the hook-arms 30.

25 I claim:

1. In a machine for bending and tempering leaf-springs, the combination, with a rotatable carrier shaft or drum, of relatively fixed and movable pressure jaws disposed parallel to said shaft or drum, pressure bars carried by said jaws and variably operable for bending and clamping a leaf-spring, means for engagement with an edge of the spring, centrally of the latter for supporting said spring against displacement while permitting it to have free flexing movements for adjustments to accommodate itself to the adjustments of the jaws, means for adjusting said supporting means relatively to the jaws, and means operative in the rotation of the shaft or drum for adjusting the jaws and clamping bars for a bending and clamping action and subsequently retracting the same.

2. In a machine for bending and tempering leaf-springs, the combination, with a rotatable carrier shaft or drum, of relatively fixed and adjustable pressure jaws disposed parallel with the axis of the drum and movable in a direction circumferentially of the drum toward and from each other, pressure bars carried by said jaws for bending and clamping a spring, means for effecting individual adjustments of the pressure bars of one jaw at least with respect to the pressure bars of the other jaws, a support movable radially of the drum and toward and from the jaws for engaging an edge of a spring blade and loosely supporting the same between the jaws to prevent displacement of the spring while permitting adjusting movements thereof in the adjustment of the jaws, means for adjusting said radially adjustable support, and means operative in the ro-

tation of the drum for moving said jaws and bars into bending and clamping position and subsequently retracting the same.

3. In a machine for bending and tempering leaf-springs, the combination, with a 70 rotatable carrier shaft or drum, of relatively fixed and adjustable pressure jaws disposed parallel with the axis of the drum and movable in a direction circumferentially of the drum toward and from each other, 75 pressure bars carried by said jaws for bending and clamping a spring, means for effecting individual adjustments of the pressure bars of at least one of the jaws with respect to the pressure bars of the other jaws, a support movable radially of the drum and toward and from the jaws for engaging an edge of a spring blade centrally thereof and loosely supporting the same between the jaws to prevent displacement of said spring 85 while permitting it to adjust itself in the adjustments of the jaws, disks carried by the drum and having cam grooves, said grooves being engageable with said support for adjusting the latter, a lever for 90 adjusting said disks, and means operative in the rotation of the drum for moving said jaws and bars into bending and clamping position and subsequently retracting the same.

4. In a machine for bending and tempering leaf-springs, the combination, with a rotatable carrier drum or shaft, of relatively fixed and adjustable pressure jaws carried by said shaft, rows of pressure bars carried by the jaws, the bars of at least one 100 of the rows being individually adjustable with relation to the other bars, means embodying fluid pressure cylinders and pistons for respectively relatively adjusting said jaws and bars in different directions, and 105 means for successively admitting fluid pressure to the respective cylinders for actuating the pistons at different points in the orbit of rotation of the shaft or drum.

5. In a machine for bending and tempering leaf-springs, the combination, with a rotatable shaft or drum, of spring bending and clamping devices carried by the drum and movable toward and from each other, fluid pressure means embodying a pair of 110 cylinders and pistons for respectively projecting and retracting said devices, and valve mechanism shiftable in the rotation of the shaft or drum for successively admitting fluid pressure to and discharging fluid pressure from the respective cylinders.

6. In a machine for bending and tempering leaf-springs, the combination, with a rotatable carrier shaft or drum, of bending and clamping devices carried by the shaft or drum and movable toward and from each other, fluid pressure means embodying a pair of cylinders and pistons for respectively adjusting said devices toward and from each other, a valve device for admit- 125 130

ting fluid pressure to and discharging fluid pressure from the respective cylinders, cams on the machine frame, and means connected with the valve and shifted in opposite directions by said cams for shifting the valve in opposite directions at different points in the orbit of revolution of the shaft or drum.

7. In a machine for bending and tempering leaf-springs, a rotary carrier shaft or drum, relatively movable jaws, sets of pressure bars on said jaws, the bars of one of the sets at least being individually adjustable for variably bending and clamping a spring edgewise radially to said shaft or drum, a supporting member engageable with an edge of the spring centrally thereof to support it while so bent and held, means for automatically moving said devices into and out of bending and clamping positions at points in the rotation of the drum or shaft, and means operative at a point in the rotation of the drum or shaft for removing the treated spring.

8. In a machine for bending and tempering leaf-springs, a rotary shaft or drum, relatively movable bending and clamping devices carried by and movable with said shaft or drum, means for adjusting the same toward and from one another at different points in the rotation of the drum, means for supporting a spring leaf bent and clamped between said devices, hook-shaped ejectors engageable with the spring leaf for engaging and removing the same after treatment, and means for actuating said hook-shaped ejectors.

9. In a machine for bending and tempering leaf-springs, a rotary carrier drum or shaft, means carried thereby for bending and clamping and subsequently releasing a spring at points in the rotation of the drum or shaft, a rock shaft rotatable with the drum, a hook-shaped spring ejector carried by said shaft for engaging and removing the spring, and contact means operative in the rotation of the drum or shaft for periodically rocking the shaft.

In testimony whereof I affix my signature.
PAUL HOBRACTH.
